(No Model.)

A. R. BRANDLY.
EYE SHADE.

No. 546,636.

Patented Sept. 17, 1895.

UNITED STATES PATENT OFFICE.

ALBERT RUSSELL BRANDLY, OF NEW YORK, N. Y.

EYE-SHADE.

SPECIFICATION forming part of Letters Patent No. 546,636, dated September 17, 1895.

Application filed February 7, 1895. Serial No. 537,597. (No model.)

To all whom it may concern:

Be it known that I, ALBERT RUSSELL BRANDLY, a citizen of the United States, residing at New York, in the county of New York and State of New York, have invented certain new and useful Improvements in Shades for the Eyes, of which the following is a specification.

The invention relates to a shade for the eyes.

The object is to provide a device in the nature of a protecting eye-shade capable of being folded to occupy a comparatively small space and adapted to be inclosed, if desired, in a case resembling more or less that used for spectacles.

With these objects in view the invention consists in the improved construction and combination of parts, to be hereinafter fully described and claimed.

Figure 1 is a view in perspective of one embodiment of the invention. Figs. 2 and 3 are detail views in perspective of a modified construction of folding joint. Fig. 4 is a view in perspective of a further modification.

In the drawings, A represents a shade, which comprises a frame a_1 , formed in two parts or sections a_2 and a_3 . The section a_2 is secured at its end to one side of the spring 30 nose-clamp a_4 , and the opposite section at its inner end is bent up in an angle to serve as a stop, it being mounted to slide in guides a_5 , which are arranged upon the upper portion of the nose-clamp. Secured to this frame and 35 extending outward therefrom is an accordion-plaited awning or canopy a_6 , formed in two sections a_7 , arranged to slide or fold one over the other, and at the ends of the awning-sections spring-fingers a_8 are secured to project 40 rearward, so as to press against the face or lower temples and thereby steady the frame.

Referring to Figs. 2 and 3 of the drawings, a modified form of joint for the frame is illustrated, and consists in forming the nose-clamp and frame of the shade in sections,

which are secured centrally by a link. A sliding collar is also provided, which, on being moved so as to inclose the joint, will render the same rigid, and when moved to either side of the joint permits of the frame and 50 guard being folded, as shown.

Referring to Fig. 4 of the drawings, the frame employed resembles somewhat that commonly used with spectacles, it being provided, however, near the center with a spring snap-joint, so as to permit of the parts or members being folded. The awning or canopy used with this form of frame, by being plaited radially, will readily fold with the frame, and constructed as last described the shade may be 60 used by a person wearing glasses without in any way interfering or causing inconvenience, as will be apparent, a rest being substituted in this instance for the nose-clamp.

Having thus fully described the invention, 65 what I claim as new is—

1. The eye-shade comprising the sectional frame, with its sections adapted to slide toward and from each other, and the sectional canopy with its sections connected to said 70 frame-sections respectively and adapted to slide one upon the other and means for connecting the shade to the nose, substantially as set forth.

2. The eye-shade comprising the nose-clamp, 75 the sectional frame, with one section connected to said nose-clamp and the other adapted to slide in guides upon said nose-clamp, and the sectional canopy with its sections connected to said frame-sections respectively and adapted to slide one upon the other, substantially as set forth.

In testimony whereof I have hereunto affixed my signature in the presence of two subscribing witnesses.

ALBERT RUSSELL BRANDLY.

Witnesses:

W. H. PUMPHREY,
F. M. JOHNSON.
